UNITED STATES PATENT OFFICE.

WALTER S. ADAMS, OF PHILADELPHIA, PENNSYLVANIA, ASSIGNOR TO JOHN A. BRILL, OF PHILADELPHIA, PENNSYLVANIA.

BRAKE MECHANISM.

SPECIFICATION forming part of Letters Patent No. 695,131, dated March 11, 1902.

Application filed December 18, 1900. Serial No. 40,238. (No model.)

To all whom it may concern:

Be it known that I, WALTER S. ADAMS, a citizen of the United States, residing in the city of Philadelphia, county of Philadelphia, 5 and State of Pennsylvania, have invented certain new and useful Improvements in Brake Mechanisms, of which the following is a specification.

My invention relates to improvements in 10 brake mechanisms or apparatus for car-trucks. Considered in some of its aspects it may be said to relate more particularly to brakes employed on pivotal trucks, in others as being especially adapted to the suspension- 15 motor type of truck—that is, where the motor is carried mainly upon the axle, but its free end is suspended from the end of the truck-frame outside the wheel-base.

It has been found troublesome in former 20 mechanisms and apparatus of this general type to maintain a proper working connection between the main brake-lever carried by the truck and the rod that runs to the source of power on the car-body when the car 25 is on a curve by reason of the divergence of the center lines of the truck and car-body. It has also been very difficult in the suspension-motor type of truck to provide a sufficient clearance between the brake mechanism 30 and the motor and still maintain a central and stable point for the application of the brake-power. My invention overcomes 35 these various objections in a simple and economical manner, first, by arranging the brake-lever substantially at the center of the truck, thus reducing the variations in connection with the rod that runs to the car-body and the source of power; second, by so constructing and locating the various parts 40 of the brake mechanism as to give ample clearance for the motor, and, third, by providing an adjustable connection between certain parts of the mechanism, whereby the pressure upon the brake-shoes can be equalized or differentiated to any degree. The latter feature is also valuable with single-motor trucks alone to obtain the exact variation of pressure desired. With this construction 45 also the advantage of an upright brake-lever is obtained in connection with outside brakes for the wheels.

My invention is illustrated by the aid of the accompanying drawings, in which the same reference characters designate like parts throughout the several views, and in 55 which—

Figure 1 is a plan view of a single-motor truck embodying my improvement. Fig. 2 is a longitudinal sectional elevation through the center of the same. 60

In these figures 1 and 2 denote the wheels and axles; 3, the sides of the frame of the truck, which contain the inverted-U-shaped yoke-pedestals 5 for the axle-boxes 6. From the said yokes extend the arms 7, forming 65 continuations of the sides of the frame, which are connected by the angle-iron cross-bars or end pieces 8^a, one or both of which may be curved outwardly, as shown at 8^a in Fig. 1, when it is desired to provide clearance for 70 the support of the free end of the motor thereon. At 9 are the usual bolster-transoms, which in this instance are secured to the brackets 3^a, formed integrally or otherwise attached to the side frames 3. 75

The brake mechanism or apparatus may be suspended from the frame in any desired manner, but preferably from the transoms and end pieces. Again, the means employed for suspension may be varied at will; but I 80 prefer the links, as shown.

Referring to Figs. 1 and 2, one set of brake-shoes 18 are fixed on the beam 17, which shoes are suspended from the end piece 8 of the frame by links 19 in the usual way. This 85 beam 17 is swung back and forth to apply or release the shoes, preferably through the medium of a brake-rod 16, which extends from the middle of the brake-beam toward the center of the truck, where it is pivotally attached, 90 as at 12°, to the lower end of a pendent equalizing-lever 12. This lever 12 is freely suspended from the middle of one of the transoms 9 by means of a hanger 10 and bolt or pin 11. It is apparent that other means could 95 be employed for the suspension of the lever 12, but that shown is deemed preferable. The other set of brake-shoes 29 are fixed to the brake-beam 28, which is curved to conform to the curve of the end piece 8^a of the 100 frame for like clearance purposes, the shoes being suspended from the end piece 8^a by

links 30 at either end. This set of shoes is brought up against or pushed away from the wheels, preferably by brake-rods 27, one at either end of the beam 28, to which they are bolted and which extends toward the center of the truck and there secured to a floating equalizing-bar 22, this bar being swung from the transom 9 above by links 21, that are movably secured to the transom by loop-hangers 20. These rods 27 are spread far enough apart to provide ample clearance for the motor therebetween. This, in connection with other details, I consider an important feature of my invention, and although it has been described with reference to specific construction shown in the drawings it is evident that many and various changes could be made therein and still come within the limits of the improvement.

20 The means for operating this mechanism preferably consists of an upright braking-lever 25, which is pivotally mounted on a pin 24 in a jaw-plate 23, secured to the bar 22, near the center thereof, and to the upper end 25 of which is connected by a pin 25^a the rod 26, running to the source of power on the car-body. A connecting-rod 15 extends between the levers 12 and 25 and is adjustably connected to them in any desired manner, but, 30 as shown, is securely pinned or pivoted at one end to the lever 25, near its fulcrum, and at its other end it is adjustably attached to the lever 12 by the pin 14 and holes 13. The function of these holes 13 is to be able 35 to cause different pressures to be placed upon the two sets of brakes. To vary the braking-pressure on the different sets of brake-shoes, it is only necessary to adjust the equalizing-lever 12 and the connecting-rod 15. This is 40 usual in single-motor-truck brakes to obtain the exact difference required. It will be noticed that this arrangement and construction allows the power end of the braking-lever 25 to be located substantially at the 45 center of the truck, thus avoiding much variation in the connection of the lever and the car-body rod when the car is on a curve. Its exact location is directly in the center of the truck transversely and only a little out of the 50 center longitudinally. The advantage thus gained is important. Another distinct advantage which results from this construction is the use of an upright lever in connection with the outside brakes—that is, brakes on the 55 other side of the wheels from the center of the truck. This results in a more advantageous arrangement of the several parts of the mechanism and a better point of application of the brake-power. A spring or springs of the desired kind can be employed to release the 60 shoes and applied in any manner suitable to the desired condition.

While I have described my invention with particular reference to the details of arrangement and construction, I wish it understood 65 that its scope is not limited thereto, as it is apparent to those skilled in the art that many

alterations, substitutions, and changes can be made therein and still come within its purview; but

70 What I do claim, and desire to secure by Letters Patent, is—

1. The combination of a pivotal truck, a brake-lever located with its power end near the center thereof, an equalizing-bar suspended from the frame of the truck and to which the lower end of the brake-lever is pivoted, 75 brake-beams, brake-shoes carried thereby and connecting mechanism between the beams and the lever.

2. The combination of a pivotal truck, a brake-lever located with its power end near the center thereof, an equalizing-bar suspended from the frame of the truck and to which the lower end of the brake-lever is pivoted, 85 brake-beams, brake-shoes carried thereby, mechanism connecting said equalizing-bar and one of said brake-beams, and mechanism capable of adjustment interposed between the remaining beam and the lever.

90 3. The combination of a car-truck having a bolster-transom, outside brake-shoes for the wheels, beams rigidly connecting the shoes for each pair of wheels and suspended from the ends of the truck-frame, an equalizing-bar connected with one brake-beam and supported from the transom, an upright main brake-lever fulcrumed near its lower end to the said bar and to the upper end of which power is applied to operate the brakes, an equalizing-lever pendent from the transom and connected near its lower end to the other brake-beam, 95 and means connecting the latter lever with the main brake-lever, whereby both sets of shoes are simultaneously operated from said main lever.

100 4. The combination of a pivotal car-truck, outside sets of brake shoes and beams for the wheels of the truck, an upright brake-lever, a transverse equalizing-bar between the 110 beams, an intermediate equalizing-lever, and intermediate connections between the bar, said levers and beams, to which brake-lever power is applied to operate the said shoes, the power end of said brake-lever being substantially at the center of the truck, and means to connect said brake-lever to the shoes.

115 5. The combination of a pivotal car-truck, outside sets of brake shoes and beams for the wheels of the truck, an upright brake-lever, a transverse equalizing-bar between the 120 beams, an intermediate equalizing-lever, and intermediate adjustable connections between the bar, said levers, and beams, to which brake-lever power is applied to operate the 125 said shoes, the power end of said lever being substantially at the center of said truck, and means to connect said brake-lever to the shoes.

130 6. The combination of a pivotal car-truck, outside sets of brake-shoes for the wheels of the truck suspended from the frame thereof, beams connecting the shoes of each set, a floating equalizing-bar suspended from the frame and operatively connected with one of

the said brake-beams, and upright main braking-lever to which power is applied to operate the brakes fulcrumed on said bar near the center thereof, and means connecting this lever with the other brake-beam.

5 7. The combination of a pivotal car-truck, sets of brake-shoes for the wheels outside the wheels' base, and suspended from the ends of the truck-frame, brake-beams rigidly connecting the shoes of each set, a floating equalizing-bar also suspended from the truck-frame, means connecting this bar to one of the brake-beams, an upright main lever fulcrumed on said bar near the center thereof, 10 an equalizing-lever fulcrumed at its upper end on the frame, means connecting its lower end with the other brake-beam, and a connecting-rod from the latter lever to the main lever. 15 8. The combination of a pivotal car-truck, sets of outside brake-shoes, beams connecting shoes of each set, means to suspend the beams and shoes from the ends of the truck-frame, an equalizing-bar suspended from supports on the frame, rods connecting this bar near 20 its ends with the brake-beam on that end of the truck, an upright main lever fulcrumed at its lower end on said bar near the center thereof, and having its other end to which power is applied located near the center of 25 the truck, a pendent equalizing-lever fulcrumed at its upper end to a support on the frame and in a line longitudinally with the main lever, a rod connecting the lower end of this lever with the other brake-beam near the center thereof, and a rod extending between 30 the two levers and connected to them intermediate their ends.

9. The combination of a car-truck frame, having end pieces and centrally-disposed transoms extending between and secured to the side pieces, brake beams and shoes suspended from said end pieces, an equalizing-bar, hangers and links to suspend the same from one of said transoms, rods one near either end 40 of said bar to connect the brake-beam on that end of the truck therewith, a jaw-plate secured to the said bar near the center thereof, a main brake-lever with its lower end fulcrumed in this plate, and its upper end to 45 which power is applied located near the center of the truck, means to connect this upper end with the source of power on the car-body, a hanger secured near the middle of the other transom, an equalizing-lever fulcrumed at its 50 upper end thereon, a connecting-rod extending from the lower end of this lever to the other brake-beam, and a connecting means between this equalizing-lever and the main lever.

60 10. The combination of a car-truck frame, brake shoes and beams suspended from the frame and arranged to brake against the outside of the wheels, means for operating said shoes including a centrally-disposed braking-lever to which power is applied, and rods connecting the said lever with one set of shoes, the rods being arranged to leave a clear open

space for a motor, and adjustable connections and a further rod leading from said lever to the other set of shoes.

70 11. In a brake mechanism, the combination of a brake-beam, shoes carried thereby and adapted to press against the wheels outside of the wheel-base, an equalizing-bar, rods connecting the beam and bar near either end so as to provide room between them for a car-motor, a braking-lever to which power is applied connected with said bar, another set of brake-shoes and means connecting this set with the braking-lever, whereby all brakes 75 may be simultaneously applied, the brakes, beam and bar all being adapted to be suspended from the frame of the truck.

12. The combination of a truck-frame, brake-beams adapted to be swung from the frame, brake-shoes thereon, an equalizing-bar also adapted to be swung from supports on the frame, rods connecting said bar with one of said beams, so as to provide clearance between them for a motor, a braking-lever to 90 which power is applied for operating the brakes and pivoted to the equalizing-bar, and a connecting-rod pivoted to said lever and its other end connected with the other beam, whereby both sets of brakes may be simultaneously applied. 95

13. The combination of a car-truck frame, brake-shoes for the wheels, beams connecting said shoes, and suspended from the frame, a floating equalizing-bar also suspended from the frame, a main brake-lever fulcrumed on the bar to which power is applied to operate the shoes, means connecting the ends of the equalizing-bar with the brake-beams on that end of the truck, said means being spaced 100 apart to provide clearance for a motor, a pendent equalizing-lever also supported from the frame, and a connecting means between said lever and said other brake-beam, and means connecting the said two levers. 110

14. The combination of a car-truck frame, brake-shoes for the wheels, beams connecting said shoes, and suspended from the frame, a floating equalizing-bar also suspended from the frame, a main brake-lever fulcrumed on the bar and to which power is applied to operate the shoes, means connecting the ends of the equalizing-bar with the brake-beam on one end of the truck, a pendent equalizing-lever also supported from the frame, a rod 115 connecting said equalizing-lever and the other brake-beam, and a rod connecting the said two levers. 120

15. The combination of a car-truck frame having end pieces and bolster-transoms extending across between the side pieces thereof, brake-shoes suspended from the end pieces, brake-beams rigidly connecting the shoes of each set, a floating equalizing-bar, links near each end thereof to suspend the same from 125 one of the bolster-transoms, rods connecting the ends of said bar with one of said beams to provide clearance between for a motor, a main brake-lever fulcrumed to said bar near

its center and to the upper end of which power is applied to operate the mechanism, an equalizing-lever suspended from the other bolster-transom near the center thereof, a rod 5 extending from the lower end of said lever to the center of the other brake-beam, and a link or rod connecting the equalizing-lever with the main operating-lever.

16. The combination of a car-truck, out-side brake-shoes for the wheels suspended from the frame of the truck, brake-beams to which the shoes are fixed, an equalizing-bar supported from the frame and inside the wheel-base, rods connecting the bar with the nearest beam, and spaced apart to provide clearance for a motor, an upright main brake-lever pivotally secured to the bar near the center of the power end of said lever being close to the center of the truck, an equalizing-lever pendent from the frame, a connecting-rod from said equalizing-lever to said main lever, and a rod connecting said equalizing-lever with the said other brake-beam.

17. The combination of a truck-frame, of brake sets pendent from the truck-frame, a transverse equalizing-bar suspended from the truck-frame and connected with one of the brake sets, a braking-lever to which power is applied for manipulating the brakes, one end 30 of which is pivotally connected to the transverse bar, an equalizing-lever depending from the frame and connected with the other brake set and an adjustable connection between the latter lever and the braking-lever for varying the pressure upon the two sets.

18. The combination of a truck-frame, brake-beams, links supporting the beams beneath the frame, a swinging equalizing-bar also supported from the frame above and connected with one of the brake-beams, a braking-lever fulcrumed on the said bar to the other end of which power may be applied, another lever pivotally suspended from the frame and connected with the other set of brakes, and a connecting-rod attached to the braking-lever and adjustably connected with the pendent lever so as to vary the pressure as desired on the two sets of brakes.

19. The combination of a car-truck frame, 50 brake-beams swingingly supported from the ends of the frame, brake-shoes fixed on said beams, bolster-transoms extending across the frame near the middle thereof, an equalizing-bar suspended from one of the transoms and rigidly connected as by rods with one of the brake-beams, a main operating brake-lever fulcrumed on the said bar to the upper end of which the brake-power is applied, an equalizing-lever suspended at its upper end from 55 the other transom, and connected firmly as by a rod with the other brake-beam, and a rod operatively connecting the latter lever with the main lever, the connection with one of them being adjustable along its length to vary 60 the brake-pressure on the shoes.

20. The combination of a car-truck frame, 65 brake-shoes suspended from the frame of the

truck, beams to which the shoes are secured, a floating equalizing-bar suspended from the frame near the transverse center of the same, 70 rods connecting the bar with one brake-beam, a main operating brake-lever fulcrumed at its lower end near the middle of the said bar, and to the upper end of which brake-power is applied, a pendent equalizing-lever sup- 75 ported on the framework near the transverse center thereof, and provided with a series of holes along its length, a rod connecting the lower end of this lever with the other brake-beam, and a connecting-rod pivoted to the 80 main lever near its lower end and capable of being joined with the equalizing-lever at any point by a pin or bolt and the series of holes.

21. The combination of a car-truck frame, 85 brake-shoes for the wheels, beams connecting said shoes and suspended from the frame, a floating equalizing-bar also suspended from the frame, a main brake-lever fulcrumed on the bar to which power is applied to operate the shoes, means connecting the ends of the 90 equalizing-bar with the brake-beam on that end of the truck, said means being spaced apart to provide clearance for a motor, a pendent equalizing-lever also supported from the frame and a connecting means between said 95 lever and said other brake-beam, and adjustable means connecting the said two levers to vary the pressure on the brakes.

22. The combination of a car-truck frame, 100 brake-shoes for the wheels, beams connecting said shoes, and suspended from the frame, a floating equalizing-bar also suspended from the frame, a main brake-lever fulcrumed on the bar to which power is applied to operate the shoes, means connecting the ends of the 105 equalizing-bar with the brake-beams on that end of the truck, said means being spaced apart to provide clearance for a motor, a pendent equalizing-lever also supported from the frame, and a rod connected between said 110 lever and the middle of the other brake-beam, and a rod adjustably connecting the said two levers, whereby the pressure on the two sets of brakes may be varied.

23. The combination of a car-truck frame 115 having end pieces and bolster-transoms extending across between the side pieces thereof, brake-shoes suspended from the end pieces, brake-beams rigidly connecting the shoes of each set, a floating equalizing-bar, 120 links near each end thereof to suspend the same from one of the bolster-transoms, rods connecting the ends of said bar with one of said beams to provide clearance between for a motor, a main brake-lever fulcrumed to said bar 125 near its center and to the upper end of which power is applied to operate the mechanism, an equalizing-lever suspended from the other bolster-transoms near the center thereof, a rod extending from the lower end of said lever to the center of the other brake-beam, and a link or rod connecting the equalizing-lever with the main operating-lever, the connection between the link or rod and one of 130

the levers being adjustable along the length thereof so as to differentiate the pressures on the brake sets to any desired degree.

24. The combination of a car-truck, outside brake-shoes for the wheels suspended from the frame of the truck, brake-beams to which the shoes are fixed, an equalizing-bar supported from the frame and inside the wheel-base, rods connecting the bar with one beam, and spaced apart to provide clearance for a motor, an upright main brake-lever pivotally secured to the bar near the center of the bar, the power end of said lever being ad-

jacent to the center of the truck, an equalizing-lever pendent from the truck-frame, a rod 15 secured between said equalizing-lever, and said main lever with an adjustable connection with one of them, whereby the pressure upon the brake-shoes may be differentiated.

Signed at the city of Philadelphia, county 20 of Philadelphia, and State of Pennsylvania, this 30th day of November, 1900.
